(57) **CLAIM**

The ornamental design for a jumpsuit, as shown and described.

DESCRIPTION

FIG. 1 is a front right perspective view of a jumpsuit, shown in the right-handed configuration;

FIG. 2 is a front left perspective view thereof;

FIG. 3 is a rear view thereof;

FIG. 4 is a front left perspective view of the jumpsuit, shown in the left-handed configuration;

FIG. 5 is a front right perspective view thereof; and,

FIG. 6 is a rear view of thereof.

The new design is a jumpsuit which provides more comfort and ease for users when needing to use bathroom facilities. The sleeve zipper is displayed in dashed lines only, and is not a part of the claimed design.

The broken lines in the drawings depict portions of the jumpsuit that form no part of the claimed design.
